(57) **CLAIM**

The ornamental design for a connector as shown and described.

DESCRIPTION

FIG. 1 is a perspective view of front, top and left side of a connector showing my new design;
FIG. 2 is a perspective view of rear, top and left side thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view of front, top and left side showing the alternate position thereof;
FIG. 10 is a perspective view of rear, top and left side showing the alternate position thereof;
FIG. 11 is a front view showing the alternate position thereof;
FIG. 12 is a top view showing the alternate position thereof;
FIG. 13 is a perspective view shown in a state of use with environmental subject matter for reference; and,
FIG. 14 is another perspective view shown in a state of use with environmental subject matter for reference.
The broken lines show portions of the article or environment that form no part of the claimed design.

1 Claim, 14 Drawing Sheets
